(57) **CLAIM**

The ornamental design for an industrial robot, as shown and described.

DESCRIPTION

FIG. 1 is a front-right-top perspective view of an industrial robot showing our new design;

FIG. 2 is a rear-left-bottom perspective view thereof;

FIG. 3 is a rear-right-top perspective view thereof;

FIG. 4 is a front-left-bottom perspective view thereof;

FIG. 5 is a right side view thereof;

FIG. 6 is a left side view thereof;

FIG. 7 is a top plan view thereof;

FIG. 8 is a bottom view thereof;

FIG. 9 is a rear view thereof;

FIG. 10 is a front view thereof; and,

FIG. 11 is a cross section taken through line 11-11 of FIG. 5 and in the area designated by lines 11' and 11" of FIG. 7, with disclaimed environmental features, such as the internal mechanisms, omitted for clarity purposes.

The broken line showing of the remainder of the industrial robot represents portions which form no part of the claimed design.

1 Claim, 11 Drawing Sheets
